Primary Examiner—Alan P. Douglas*Assistant Examiner*—Antoine D. Davis*Attorney, Agent, or Firm*—Kenneth W. Iles**[57]****CLAIM**

The ornamental design for a folding wallpaper cutting board, as shown and described.

DESCRIPTION

FIG. 1 is a top, right front perspective view of a folding wallpaper cutting board in the unfolded position showing my new design;

FIG. 2 is a fragmentary cross section taken along line 2—2 of FIG. 1;

FIG. 3 is a front elevation view in the folded position;

FIG. 4 is a top plan view in the unfolded position;

FIG. 5 is a front elevation in the unfolded position;

FIG. 6 is a rear elevation in the unfolded position;

FIG. 7 is a bottom plan view in the unfolded position;

FIG. 8 is a left side elevation in the folded position; and,

FIG. 9 is a right side elevation in the folded position thereof.
